PAPER HANDLING

John Q. Sherman, Dayton, Ohio

Application August 7, 1931, Serial No. 555,811

18 Claims. (Cl. 197—133)

My invention relates to paper handling and, in particular, to the feeding of a large number of multiple continuous length forms in registration with each other.

5 It is a special object of my invention to provide a synchronous pin wheel feed adapted to feed a large number of multiple continuous length forms in registration with each other, such forms being supplied from a common source and being delivered in a common group of aligned forms.

10 It is a further object to provide a method of feeding in which a group of superimposed continuous length forms is supplied, separated into groups, aligned in separate groups, each group being aligned synchronously with the aligning of the other group, and will pass the printing point on the platen in aligned condition in a single group in registration one with the other.

15 It is impossible to feed continuous length forms without having some device to continually adjust them and to take up the discrepancy in alignment between the several sheets, accumulation of which discrepancies would soon throw the forms out of registration with each other.

20 In a pin wheel feed where it is necessary to have the pins enter through holes punched in the printed forms and to go through holes in interleaved carbon paper when used in this manner and traveling in an arc during the radial feed 25 of the pin bearing bodies (the condition of the pins being that some are always entering the holes, others are fully engaged and others are leaving the holes), registration can only be obtained at a limited number of copies because of an overlapping of forms slightly at the holes due to discrepancies constantly appearing.

25 I have found in practice that it is possible to feed eight or ten superfolded forms at one time with one pin wheel, but, where an increasing number is required, such as fifteen or eighteen copies, it is not possible to successively penetrate so many forms through the holes without mutilation.

30 The paper discrepancies themselves are added to due to the fact that the forms are fed circumferentially around the platen, thus causing each superimposed form to travel around a greater circumference.

35 When alignment is maintained at one point, as preferably at or near the writing point, a continual, increasing lack of registration appears the farther you go around the platen away from the writing point. It is a particular object of my invention, as one embodiment of it, to provide pin wheels which can individually, succee-

sively handle eight or ten sheets, and by synchronizing the movement of the two pin wheels, together by suitable gearing and by separating forms into sets for each pin wheel as they proceed from a common supply to the pin wheel, I am enabled to accomplish the foregoing objects.

40 I separate the forms into two sets after they leave the printing point, but, before reaching the pin wheel feeds. The separation is accomplished by a guide plate, of which one type is illustrated in the accompanying drawings.

45 Referring to the drawings:

Figure 1 is an isometric perspective of a typewriter in which the mechanism of my invention has been installed and on which my method is practiced;

Figure 2 is an isometric perspective of my separator;

Figure 3 is a side elevation of my synchronized pin wheel feed and separator;

Figure 4 is a front elevation of the pin wheel feed;

Figure 5 is a detail view of one form of typewriter friction feeding mechanism, which is adjusted to inoperable position when this invention is applied to the typewriter;

Figure 6 is an end view of the pin wheel feed.

It will be noted that it is desirable that one pin wheel be set either slightly ahead of or apart from the other so that the pins from one feed do not touch those of another feed. The pin wheels themselves are so synchronized that, while one pin wheel is feeding at a little different position from the other, it is so set as to maintain the forms of the two sets in registration with each other. The forms of the one set originally printed on are divided into two sets.

Referring to the drawings in detail, I designate a typewriter having the usual keys 2 actuating the type faces 3 on the type-carrying bars 4.

40 In Figure 3 a type face 3 is shown at the printing point on the typewriter platen 5 around which a plurality of multiple continuous length forms in registration must be fed. This group of forms, as it is supplied around the platen, is designated 6.

45 Mounted on the platen shaft 7 is a master gear 8 meshing with an intermediate pinion 9, which, in turn, engages the gear 10 on the shaft 11, which shaft carries the pin wheel drum 12 carrying the pins 13.

50 Returning to the gear 9, it will be noted that it also meshes with the gear 14 which drives the gear 15 on the shaft 16 carrying the pin wheel drum 17 and the series of pins 18.

55 If desired, an eccentrically-arranged drum 55

guard 19 may be provided surrounding the pin wheel shaft and eccentrically disposed with respect to the pins, the pins progressively and successively passing through the slots 20 and 21 whereby the drum surface acts as a stripper for stripping the groups of sheets that are being aligned by and upon the pins.

In order to permit each group of pins 13 and 18 to handle a number of sheets which the pins are capable of handling with speed and accuracy, I provide a separator of the form shown in Figures 2 and 3 which comprises a pair of arcuate plates 22 and 23 having slots 24 and 25 at either end, through which the pins 13 and 18 pass. The strips of paper arranged in groups are separated into those groups and pass over the surfaces of the plates 22 and 23 where they are aligned by the respective sets of pins 13 and 18 after which they may be brought together into the aligned group of sheets as at 26.

These separator plates 22 and 23 are supported at their respective ends by the arms 27 mounted on the shaft 28 which is suitably supported in the side frame members 29 of the machine. A latch member 30 engages with a shoulder 31 or a shoulder 32 to maintain this separator either in its horizontal or vertical position. A thumb piece 33 is used for actuating the latch which is pivoted at 34 on the side plate 29.

30 By employing this wedge-shaped, separating plate construction, it is unnecessary to set one pin wheel ahead of the other because the double plate shape provides clearance enough for the pins of each feeding device to feed in the same relation and clear each other. If a flat plate is used, it is necessary to set one pin wheel slightly ahead of the other and adjust them to feed synchronously to keep the forms of each set in alignment in order to secure a perfectly aligned set of 40 sheets.

It will be understood that a style of pin wheel of the retractible or disappearing pin type may also be used in this combination.

Having thus fully described my invention, what 45 I claim as new and desire to secure by Letters Patent, is:

1. In a method of aligning sheets having a plurality of marginal apertures, arranging a group of said sheets in substantial alignment with one another, feeding said sheets as a group, separating said sheets into separate groups, aligning all of said sheets with reference to each other in the original group by separate means operating on the marginal apertures of each separate group.

55 2. In a method of handling multiple continuous length forms having marginal perforations, assembling in a group in substantial alignment, feeding as a group, separating in divergent groups, aligning all of said forms with reference to each other in the original group by separate means operating on the marginal perforations of each 60 separate group.

65 3. In a method of aligning multiple continuous length forms having marginal perforations, feeding said forms as a group, printing on said forms as a group, separating said forms into groups, aligning all of said forms with reference to each other in the original group by separate means operating on the marginal perforations of each 70 separate group.

75 4. In a method of aligning multiple continuous length forms having marginal perforations, feeding said forms as a group, printing on said forms as a group, separating said forms into divergent groups, aligning said divergent groups through

the agency of the marginal apertures, and synchronizing the aligning of said separate groups so that they are aligned together equally and simultaneously even though in separate groups.

5. In a method of aligning multiple continuous length forms having marginal perforations, feeding as a group, separating into independent groups, and aligning through the agency of the marginal apertures each group simultaneously and synchronizing equally one group with the 10 other group. 5

6. In a method of aligning sheets having a plurality of marginal apertures, arranging a group of said sheets in substantial alignment with one another, feeding said sheets as a group, separating said sheets into separate groups, synchronously aligning said sheets by the marginal apertures in separate groups while so separated. 15

7. In a method of handling multiple continuous length forms having marginal perforations, assembling in a group in substantial alignment, feeding as a group, separating in divergent groups in divergent paths, inserting pin aligning devices in the perforations of each group for aligning each group, and means to synchronously actuate said 25 pin aligning devices to align each group while separated from the other group.

8. In a typewriter handling multiple continuous length forms having marginal perforations fed around a platen, means for feeding said forms 30 and separating them in groups from a common supply, pin wheel devices engaging the apertures in the respective groups, and means for synchronously aligning said groups.

9. In a typewriter handling multiple continuous length forms having marginal perforations fed around a platen, means for feeding said forms 35 in groups from a common supply, consisting of pin wheel devices engaging the apertures in the respective groups, means for synchronously aligning said groups, and means for separating said groups into divergent paths for delivery to each of said pin wheel devices. 40

10. In a typewriter handling multiple continuous length forms having marginal perforations 45 fed around a platen means for feeding said forms and separating them into groups from a common supply, said means including a pair of arcuate plates and, means for synchronously aligning said groups. 50

11. In combination with a typewriter handling multiple continuous length forms having marginal perforations, a platen for feeding a plurality of said forms as a single group, spaced pin wheels, means of separating said group into a plurality 55 of groups, the spaced pin wheels engaging the apertures in the respective groups for aligning them, and means to synchronously drive said pin wheels and platen.

12. In combination with a typewriter handling 60 multiple continuous length forms having marginal perforations, a platen connected to spaced pin wheels for feeding a plurality of said forms as a single group, means of separating said group into a plurality of groups, the spaced pin wheels engaging the apertures in the respective groups for aligning them, means to synchronously drive said pin wheels and platen, and means to strip said groups of sheets from the respective pin wheels. 65

13. In combination in a typewriter wherein multiple continuous length forms with marginal perforations are fed around a typewriter platen, a typewriter platen having means for printing on sheets fed therearound, means for separating said sheets in divergent paths, means for engag. 70 75

ing the marginal perforations of each group of sheets comprising pin wheels, and means of synchronously operating said pin wheels for synchronous, simultaneous, identical alignment of each group of sheets.

14. In combination, a pin wheel, and a slotted spacer having oppositely curved walls adjacent said pin wheel, the teeth of said pin wheel projecting through one wall of the spacer.

10 15. In combination, a pair of spaced pin wheels, means for driving said pin wheels synchronously, a pair of arcuate plates joined at their margins having slots therein for receiving said pins located between said pin wheels, whereby a group 15 of paper sheets are separated into groups by said plates and fed by the pin wheels.

15 16. In combination, a pair of spaced pin wheels, means for driving said pin wheels synchronously, a pair of arcuate plates joined at their margins 20 having slots therein for receiving said pins lo-

cated between said pin wheels, whereby a group of paper sheets are separated into groups by said plates and fed by the pin wheels, and eccentrically arranged, pin wheel stripping drums having slots for receiving the pins of the pin wheels associated with each of said pin wheels in spaced relationship to said plates.

17. A new article of manufacture for use as a separator for a plurality of groups of sheets comprising supports, a pair of arcuate convex plates joined along their marginal edges having slots in the faces thereof for the reception of pins on pin wheels.

18. In combination, a pair of spaced pin wheels having pins, a swinging separator comprising spaced arcuate plates located between said pin wheels and having slots for receiving the pins thereon, and means of pivotally supporting said plates from a point remote from said pin wheels.

JOHN Q. SHERMAN. 20
